[57] CLAIM

The ornamental design for a volatile dispenser, as shown and described.

DESCRIPTION

FIG. 1 is a front perspective view, from above and to one side, of a volatile dispenser showing the new design.

FIG. 2 is a front elevational view of the volatile dispenser of FIG. 1, the back, left, and right elevational views being identical thereto.

FIG. 3 is a top plan view of the volatile dispenser of FIG. 1; and,

FIG. 4 is a bottom plan view of the volatile dispenser of FIG. 1.
